CATALYTIC CONVERTER

Charles E. Fisher, La Mirada, Calif., assignor to Norris-Thermador Corporation, Los Angeles, Calif., a corporation of California

Filed July 30, 1962, Ser. No. 213,211

4 Claims. (Cl. 23—288)

The present invention relates to catalytic converters employed in internal combustion engine exhaust systems for catalytically oxidizing previously unoxidized or only partially oxidized components of the exhaust gases which are harmful when released into the atmosphere, such as hydrocarbons and carbon monoxide, and it relates particularly to a novel catalytic converter construction which permits a maximum amount of catalyst to be embodied within the converter, which provides relatively even temperature distribution throughout the catalyst bed without damaging "hot spots" tending to develop, and wherein the parts of the converter are so arranged that bypass channels cannot develop in the catalyst bed through which the exhaust gases would pass untreated, even though a considerable quantity of catalyst material may have been lost due to attrition or other causes.

Although various devices have been proposed for use in vehicles with internal combustion engine exhaust systems for reducing or eliminating "smog"-forming and other harmful exhaust gas components, such as unburned or partially burned hydrocarbons and carbon monoxide, the most practical and efficient apparatus for accomplishing this appears to be the catalytic converter which is employed in the exhaust system as a replacement for the conventional muffler. Such a catalytic converter has a catalyst disposed therein, usually a bed of particulate catalyst material, which promotes oxidation of such previously unburned or only partially burned exhaust components, and this chemical action is exothermic, i.e., produces heat.

However, contemporary vehicles with their relatively limited road clearance impose structural limitations on catalytic mufflers or converters, the limitations being such that the overall volume of the muffler is relatively limited, and the depth of the muffler between the top wall and the bottom wall is generally required to be less than the width between the side walls, the muffler having a generally flattened, oval cross-sectional shape. These structural limitations make it difficult to provide a sufficient quantity of catalyst material in the muffler for efficient oxidizing of the undesired exhaust ingredients, while at the same time directing the flow of exhaust gases through the catalyst in such a manner as to avoid the formation of "hot spots" in the catalyst bed or the development of bypass channels through the bed, and so as to most effectively utilize the catalyst that is present and to avoid localized contamination or "poisoning" of the catalyst by lead compounds in the exhaust.

It has been found desirable in practice to have the exhaust gases flow vertically, either downwardly or upwardly, through a relatively wide, flat catalyst bed, in order to make the most efficient use of the catalyst and to avoid "poisoning" of the catalyst by lead compounds which is likely to occur if the exhaust gases flow longitudinally through a catalyst bed of relatively narrow cross-section. However, prior art vertical flow arrangements in catalytic mufflers of generally flattened form usually resulted in a large waste of the available volume in the case because of excessively large plenum chambers, so that the amount of catalyst employed was seriously restricted.

Another disadvantage of most prior art catalytic mufflers, and particularly those of the vertical flow type, was

2

that heat transfer within the catalyst bed was relatively slow, resulting in delayed activation of the catalyst during engine warm-up, and because of this poor heat transfer and uneven contact of the exhaust gases with various portions of the catalyst bed, "hot spots" tended to develop in the catalyst bed, which could cause damage to the catalyst, the muffler case, and possibly surrounding structure of the vehicle.

Further, in many prior art catalytic mufflers, including those of the vertical flow type, it has been found that loss of catalyst due to attrition or other causes provides a bypass or escape paths for the exhaust gases through the muffler without effective contacting of the catalyst material.

Accordingly, it is an object of this invention to provide a catalytic muffler wherein the configuration and dimensions thereof may be substantially the same as those of conventional mufflers, and the arrangement of the structure of the catalytic muffler provides for the utilization of a maximum quantity of catalyst material.

Another object of the present invention is to provide a catalytic muffler or converter of the character described wherein the parts thereof are so arranged that bypass channels or escape paths cannot develop in the catalyst bed through which the exhaust gases can pass untreated, even though a considerable quantity of catalyst material may have been lost due to attrition or other causes.

Another object is to provide a catalytic muffler of the general character described wherein there is a relatively rapid transfer of heat from the input portion of the catalyst bed to the remainder of the bed, thus to accelerate activation of the entire catalyst bed during engine warm-up, and wherein the temperature distribution throughout the catalyst bed is maintained relatively uniform during operation and localized "hot spots" will not tend to develop.

A further object of this invention is to provide a catalytic converter of the aforementioned character wherein there is provided an inlet plenum tube for exhaust gases which is partitioned from an outlet plenum tube by a baffle, the tubes normally being substantially surrounded by the catalyst material and being in close proximity to each other to thereby provide a relatively rapid transfer of heat to the catalyst material, and to also provide a relatively uniform temperature distribution throughout a major portion of the catalytic converter.

A more specific object of this invention is to provide a catalytic converter of the aforementioned character wherein even though the inlet and outlet plenum tubes are in relatively close proximity to each other, the flow path for the exhaust gases from the inlet plenum tube to the outlet plenum tube through the catalyst material is relatively extensive.

A yet further object of this invention is to provide a catalytic converter of the aforementioned character wherein the exhaust gases passing through the converter follow a generally vertical flow path.

A serious problem exists in connection with catalytic converters which is that under certain conditions of engine operation, excessively high concentrations of unburned materials are produced by the engine and passed through the exhaust systems, which results in the production of an excessive amount of heat in the catalytic converter. This excessive heat production in the catalytic converter can damage the converter case, and could even be damaging to adjacent underside parts of the vehicle, such as brakes or the like. Excessive heat in the converter will also tend to accelerate oxidation of the metal which forms the converter case, thus further tending to reduce the life of the converter.

In view of the immediately preceding problem, it is

an object of this invention to provide a catalytic converter of the aforementioned character wherein excessive heat production in the catalyst material will result in actuating a valving system to make available to the exhaust gases a passage through the converter which bypasses the catalyst, until such time as the temperature of the catalyst returns to acceptable limits.

Further objects and advantages of the present invention will appear during the course of the following part of the specification wherein the details of construction and mode of operation of a preferred embodiment are described with reference to the accompanying drawings, in which:

FIGURE 1 is a longitudinal, vertical sectional view, partly in elevation, illustrating the catalytic converter together with a portion of the valving system for controlling the direction of flow of the exhaust gases through the converter.

FIGURE 2 is a horizontal sectional view, partly in elevation, taken on irregular line 2-2 of FIGURE 1.

FIGURE 3 is a cross-sectional view taken on line 3-3 of FIGURE 1, showing the inlet plenum tube partitioned from the outlet plenum tube and illustrating both tubes substantially surrounded by catalyst material.

Exhaust gases having unoxidized and only partially oxidized components therein are delivered from an internal combustion engine to catalytic converter 10 through exhaust pipe 12, the exhaust pipe being fastened to catalytic converter 10 by a typical flange connection 14. Catalytic converter 10 includes an elongated case 16 which is oval-shaped in cross-section, see FIGURE 3, and which embodies a relatively flat top wall 18, a relatively flat bottom wall 20, a pair of substantially semi-cylindrical side walls 22, a front or forward wall 24, and a rear or back wall 26.

Disposed in case 16 is a perforate inlet plenum tube 28 which is partitioned from a perforate outlet plenum tube 30 by a horizontal baffle plate 32. Baffle plate 32 is supported in case 16 substantially midway between top 18 and bottom wall 20 by vertical struts 33 and by connection with end walls 24 and 26. Plenum tubes 28 and 30 are in vertical alignment, and together with baffle plate 32, the plenum tubes are coextensive in length with case 16. Additionally, plenum tubes 28 and 30 are equally spaced inwardly from both side walls 22 so as to vertically partition case 16 into a pair of substantially identical compartments 34 and 36, each of which has substantially the same volume as the other and each of which is filled with a catalyst material, preferably in particulate form, so as to provide a pair of spaced catalyst beds 38 and 40, which may be considered a single catalyst bed, all of which will hereinafter be described in more extensive detail.

Forward wall 24 of case 16 encloses the forward end of compartments 34 and 36, and rear wall 26 encloses the rear end of the compartments so as to prevent the loss of catalyst material. However, the forward wall has a pair of vertically aligned openings 42 and 44 therein which provide access to plenum tubes 28 and 30, respectively. Joined to the exhaust pipe 12 at flange 14 is a neck 46 which divides into upper and lower conduits 50 and 52, respectively, which are joined at a common wall 54, the conduits 50 and 52 being welded or otherwise fastened to the forward wall 24, with upper conduit 50 in communication with plenum tube 28 and lower conduit 52 in communication with plenum tube 30.

The flow of exhaust gases into conduits 50 or 52 is controlled by a valving system 58, which includes a butterfly valve 60 disposed in conduit 50 and a butterfly valve 62 disposed in conduit 52, valving system 58 being hereinafter described in more extensive detail.

Under normal temperature conditions in the catalyst bed the exhaust gases flow through upper conduit 50 through open butterfly valve 60, thence into inlet plenum tube 28 and then through catalyst beds 38 and 40, and

into outlet plenum tube 30 from where they are discharged. However, flowing of the exhaust gases into plenum tube 28 is dependent on the temperature of catalyst beds 38 and 40.

Most, if not all, catalysts employed in catalytic converters produce an exothermic reaction when reacting with exhaust gases; i.e., heat is produced. As a result there is an acceptable temperature operating range, and when this range is exceeded due to unusually large quantities of combustible materials being exposed to the catalyst, damage to the catalyst, catalytic converter and vehicle can occur, as before mentioned. When the temperature range is exceeded, valving system 58 prevents the flow of exhaust gases into inlet plenum tube 28 and instead directs the exhaust gases through conduit 52 through open butterfly valve 62, and thence into outlet or discharge plenum tube 30.

Discharge plenum tube 30 is in direct linear alignment with an opening 64 in rear wall 26 midway between side walls 22 and adjacent the bottom wall 20, and communicating with opening 64 is a tubular extension 66 which is welded or otherwise fastened to rear wall 26. Extension 66 is fastened to an exhaust gas discharge pipe 68 by a typical flange connection 70. Thus, it may be seen that gases entering discharge plenum tube 30 from conduit 52 flow directly out of catalytic converter 10 and bypass catalyst beds 38 and 40.

However, exhaust gases following the normal flow path are received in inlet plenum tube 28, which is generally U-shaped in cross-section. The open side of inlet plenum tube 28 is closed by top wall 18. Each leg of inlet plenum tube 28 has an outwardly extending flange 71 thereon which is employed to fasten inlet plenum tube 28 to case 16, preferably by welding. The bight of inlet plenum tube 28 is adjacent to horizontal baffle plate 32.

Exhaust gases flow from inlet plenum tube 28 into both catalyst beds 38 and 40, and since the width of baffle plate 32 is greater than the width between the legs of inlet plenum tube 28, the exhaust gases are required to assume a horizontal as well as a vertical flow path in order to pass around baffle plate 32 and into outlet plenum tube 30 through the perforated wall thereof.

Outlet plenum tube 30 is substantially identical to inlet plenum tube 28; i.e., it is U-shaped in cross-section, but it is inverted with the open side being closed by bottom wall 20. Outwardly extending flanges 72 on each leg are employed to fasten outlet plenum tube 30 to bottom wall 20, preferably by welding, and the bight of outlet plenum tube 30 is adjacent to baffle plate 32.

Thus it may be seen, because of the relatively close proximity of the plenum tubes to each other and to baffle plate 32, that heat from hot exhaust gases entering inlet plenum tube 28 is efficiently conducted or transferred to baffle plate 32 and outlet plenum tube 30, and this heat is also efficiently and generally uniformly transferred to the catalyst beds 38 and 40. Additionally, because the plenum tubes 28 and 30 and catalyst beds 38 and 40 are coextensive, a relatively uniform temperature is maintained throughout the catalyst beds, and the occurrence of "hot spots" is generally avoided.

Exhaust gases entering outlet or discharge plenum tube 30 from catalyst beds 38 and 40 flow from plenum tube 30 through extension tube 66 and into discharge pipe 68 where they are discharged to the atmosphere.

A feature of particular significance is the novel arrangement of catalyst beds 38 and 40. There can be as much as about 50% loss of catalyst material due to attrition or other causes, and still the exhaust gases flowing from inlet plenum tube 28 to outlet plenum tube 30 will be thoroughly treated to oxidize those unoxidized or only partially oxidized components of the exhaust gases. For instance, the level of catalyst beds 38 and 40 may fall to approximately the level of baffle plate 32. With the catalyst beds at this level exhaust gases must still flow through the catalyst material in order to enter outlet

plenum tube 30, and with the catalyst beds at this level no bypass or escape paths are available which would enable the exhaust gases to enter outlet plenum tube 30 without being treated. By having the exhaust gases flow downwardly through the converter rather than upwardly, the particulate catalyst tends to be packed in the lower part of the converter case, even if part of the catalyst has been lost, thus further insuring against development of bypass channels through the catalyst beds.

As previously mentioned, valving system 58 is responsible for controlling the direction of flow of the exhaust gases. This valving system includes a diaphragm actuator 76 which is supported at the forward end of case 16. Actuator 76 is connected to the intake manifold 78 of the engine through vacuum conduit 80, and vacuum conduit 80 has a valve 82 therein which is mounted on case 16 of catalytic converter 10. Valve 82 includes a temperature sensing probe 84 which extends into catalyst bed 38 substantially midway in the flow path of the exhaust gases from inlet plenum tube 28 to outlet plenum tube 30. Therefore, although probe 84 is located to one side of case 16, it is in a position to obtain an average sampling of the temperature occurring within catalyst bed 38, and the temperature of catalyst bed 38 is also representative of the temperature of catalyst bed 40.

Temperature sensing probe 84 may be any suitable thermo-mechanical device capable of actuating valve 82, as for example a coaxial rod and tube arrangement wherein the rod and tube have different coefficients of thermal expansion.

When the temperature in catalytic converter 10 is below the normal operating range or within the normal operating range, the temperature sensing probe 84 holds valve 82 in its open position so that the partial vacuum condition within intake manifold 78 is communicated through vacuum conduit 80 to diaphragm actuator 76, and with valve 82 in this condition the exhaust gases flow into upper conduit 50 and into inlet plenum tube 28. However, when the temperature in catalytic converter 10 rises above a predetermined value, sensing probe 84 will cause valve 82 to close, so that the intake manifold 78 does not communicate with diaphragm actuator 76 through vacuum conduit 80, and with valve 82 in this condition the flow of exhaust gases will be diverted through lower conduit 52 and directly into and through outlet plenum tube 30.

A shaft 86 is slidably connected to diaphragm actuator 76, and connected to a free end of shaft 86 is a linkage system 88 which is connected to butterfly valves 60 and 62.

Butterfly valve 62 will render conduit 52 closed to exhaust gases and butterfly valve 60 will render conduit 50 open to exhaust gases when the temperature of the catalytic converter is below or within the acceptable temperature operating range and valve 82 is open, with the result that exhaust gases will flow into inlet plenum tube 28, through catalyst beds 38 and 40, thence into outlet plenum tube 30 from where they flow into discharge pipe 68 and then into the atmosphere. However, when the temperature of catalyst beds 38 and 40 exceeds the predetermined operating value, valve 82 will close in response to the temperature rise which results in diaphragm actuator 76 causing shaft 86 to actuate the linkage system 88 to cause butterfly valve 60 to render passage 50 closed, and butterfly valve 62 to open passage 52. The exhaust gases will then enter outlet plenum tube 30 and be discharged therefrom in the aforementioned manner.

While the instant invention has been shown and described herein in what is conceived to be the most practical and preferred embodiment, it is recognized that departures may be made therefrom within the scope of the invention, which is therefore not to be limited to the

details disclosed herein, but is to be accorded the full scope of the claims.

Having described my invention, what I claim as new and desire to secure by Letters Patent is:

- 5 1. A catalytic converter for treating exhaust ingredients produced by an internal combustion engine, comprising: a case defining a chamber having opposed ends; an inlet plenum tube having an elongated perforated portion in said chamber extending substantially from end to end thereof; an outlet plenum tube having an elongated perforated portion in said chamber and extending substantially from end to end thereof in parallel and overlapping relation to said elongated perforated portion of said inlet plenum tube and in close proximity thereto; a heat conductive baffle plate between and parallel to said portions and extending substantially the entire length of said portions, said baffle extending laterally a substantial distance beyond the sides of said portions and terminating in opposed edges spaced inwardly from opposite sides of said chamber; and a bed of particulate catalyst material substantially filling said chamber and encompassing substantially all surfaces of said portions exposed within said chamber and said baffle plate whereby to define an extended flow path for exhaust gases from said inlet portion 10 to said outlet portion, through said material and around said baffle while providing a short heat conductive path from the region adjacent one portion to the region adjacent the other portion through said baffle plate.
- 15 2. A catalytic converter as defined in claim 1 wherein 15 said plenum tube portions and said baffle plate are in direct heat conductive contact substantially throughout their lengths.
- 20 3. A catalytic converter as defined in claim 1 wherein 20 said plenum tube portions and said baffle plate are in direct contact substantially throughout their lengths and define a partition across said chamber between said opposite sides.
- 25 4. A catalytic converter as defined in claim 1 wherein 25 said chamber is of generally flattened oval shape in transverse cross section, having generally flat top and bottom wall portions; said baffle plate being positioned generally centrally between said top and bottom wall portions and said opposed edges being spaced from said sides a distance about the same as the distance between said baffle 30 plate and said top and bottom wall portions.
